UNITED STATES PATENT OFFICE

FRANK BAUER, OF EWING, NEBRASKA

CATTLE GUARD

Application filed November 11, 1931. Serial No. 574,409.

The present invention relates to a cattle guard to prevent cattle from passing through an opening in a fence or the like which is provided for the passage of automobiles, trucks and the like and the prime object of the invention resides in the provision of a guard of this nature which will permit the passage of an automobile or truck thereover at which time the weight of the automobile will cause platforms normally inclined to swing down to a flat position, there being means to return the platforms to their normal inclined positions after the automobile or the like has passed thereover.

Another very important object of the invention resides in the provision of a cattle guard of this nature which is simple in its construction, inexpensive to manufacture, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a top plan view of a cattle guard embodying the features of my invention.

Figure 2 is a vertical longitudinal section therethrough.

Figure 3 is a detail section taken substantially on the line 3—3 of Figure 2, and

Figure 4 is a detail section taken substantially on the line 4—4 of Figure 2.

Referring to the drawings in detail, it will be seen that the letters P denote generally a pair of platforms. Each platform comprises a pair of spaced parallel coextensive longitudinal bars 5 across which are a plurality of spaced parallel coextensive cleats 6. Adjacent ends of the bars 5 of the two platforms are rockable on a transversely disposed rod 7 the ends of which are mounted in hangers 8 which are pivotally suspended from ends of rockers 9. These rockers 9 are rockably mounted intermediate their ends as at 10 between pairs of posts 11 rising from the

ground, one pair to each side of one of the platforms P.

On the ends of the rockers 9 remote from the hangers 10 are suitable weight elements 12 sufficient to normally hold the platforms in the inclined position shown in Figure 2.

Two pairs of guide posts 14 are provided and the weighted ends of the rockers move therebetween and are limited in their upward movement by cross pins 15.

It will be readily appreciated that when the platforms are in inclined positions as shown in full lines in Figure 2 an automobile, truck or the like may run up on one of the platforms and the weight of the truck will cause the platforms to swing down to the flat dotted line position of Figure 2 so that the vehicle may easily pass thereover and after having passed thereover the rockers will lift the platforms to their normal inclined position so as to prevent cattle from passing through the driveway in the fence or the like.

It is thought that the construction, operation, utility and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It is apparent that changes in the details of construction may be resorted to without departing from the spirit or scope of the invention as hereinafter claimed or sacrificing any of its advantages.

Having thus described my invention, what I claim as new is:

In a cattle guard, a pair of platforms having overlapping portions, a rod extending transversely through the overlapping portion of the platform, hangers pivotally connected to said rod and extending upwardly therefrom, rockers having pivotal connection with the upper portions of said hangers, weights mounted on the outer portions of

said rockers, pairs of standards supporting the rockers for rocking motion intermediate the ends thereof, and pairs of guide plates for guiding the rockers in vertical motion and having means to limit the rocking motion of the same.

In testimony whereof I affix my signature.
FRANK BAUER.
